UNITED STATES PATENT OFFICE

HARRY A. HIGGINS, OF DETROIT, MICHIGAN, ASSIGNOR TO DIAMOND POWER SPECIALTY CO., OF DETROIT, MICHIGAN.

BLOWER FOR BOILERS.

1,042,676.

Specification of Letters Patent.

Patented Oct. 29, 1912.

Application filed July 5, 1911. Serial No. 636,931.

To all whom it may concern:

Be it known that I, HARRY A. HIGGINS, a citizen of the United States of America, residing at Detroit, in the county of Wayne and State of Michigan, have invented certain new and useful Improvements in Blowers for Boilers, of which the following is a specification, reference being had therein to the accompanying drawings.

10 This invention relates to boiler flue cleaners, and it has for one of its objects the provision of an improved mechanism for actuating the same.

15 The invention has furthermore for its object the provision of means whereby the parts which are exposed to the flames issuing through the boiler flues, may be guarded against burning out, more especially pertaining to the steam or distribution pipe 20 which is in the present instance jacketed by fire-proofing material such as asbestos or the like.

25 Further objects of the invention will hereinafter appear and be particularly defined in the claims.

The invention has been clearly illustrated in the accompanying drawings in which similar characters denote similar parts, and in which—

30 Figure 1 is a fragmental vertical section of the rear wall of a boiler-setting having my improved blower applied thereto; Fig. 2 is a front view of the operating mechanism; Fig. 3 represents a top view with 35 the blower in its "retracted" position, and Fig. 4 is a detail of the steam-distributing or "blower" pipe.

In the drawings 10 denotes a rear portion 40 of a boiler setting within which is disposed a boiler shell 11 having flues 12. Held in the rear wall of the setting is a stationary cylindrical tube 13 provided at its inner end with a cap 13' for packing and holding a sleeve 14 in which a steam pipe 15 is mounted for longitudinal and rotative movements. The inner end of the tube has a distributing pipe 16 extending radially therefrom and provided with a series of nozzles 17 so arranged that when said pipe 15 is rotated, the 50 nozzles will blow steam into the ends of the several boiler tubes 12.

The outer end of the steam pipe 15 carries a screw-threaded collar-yoke 18 provided with a hub 19 in which an operating

rod 20 may be secured in any suitable manner, this rod extending through a stuffing box 21 formed in a head casing 22 which is tightly attached to the cylindrical tube 13, the casing being in open communication with a steam-supply pipe 23 provided with a shut-off valve 24. A stub-lever 25 is pivoted on the outer end of the stem 20 and carries one end of a link 26 which has a pin 27 adapted to be placed into any one of a series of apertures 28 formed in a bracket 65 arm 29 which preferably extends horizontally from the casing 22 and is secured to an extension 22' thereof. According to the space between the rear wall of the boiler setting and the boiler room, the pin 27 may 70 be placed so that a lever 30 placed in the stub-lever 25 may have the required room to swing in for the purpose of projecting the steam pipes, into the combustion space S (as shown in Fig. 1), or to withdraw the 75 same into position shown in Fig. 3, in which the distributor pipe is illustrated resting upon a metal-covered ledge 31 formed in the boiler wall. Hence it will be seen that the products of combustion cannot come into 80 direct contact with the pipe.

Means are provided for guarding the steam pipe against burning-out, these means consisting of a jacket of asbestos A or the like surrounding said pipe and inclosed by 85 a casing-hub 32. In a similar manner the free end of the pipe or its end-cap 33 is protected by an asbestos disk 34 held in place by a cap 35 in engagement with the casing tube 32. By this construction the life of the 90 distributing pipe is very much enhanced, and if desired, the elbow 36 whereby the steam pipe and distributor are connected may have ribs 36' between which asbestos packed in place to protect the same from the 95 flame issuing through the flues.

I claim:—

1. The combination with a steam supply pipe, of a steam-tube rotatable and longitudinally movable in said pipe, a distributor 100 pipe radially extending from said tube, and a linkage comprising an oscillatory lever having a fulcrum-connection with and for controlling said tube to swing the distributor pipe and also to move the same with said 105 tube into projected or retracted position.

2. The combination with a steam supply pipe, of a steam-tube rotatable and longitu-

- 22
1. radially movable in said pipe, a distributor pipe radially extending from said tube, a yoke carried by said tube, a rod attached to the yoke and extending through said tube, 5 and a linkage comprising an oscillatory lever having a fulcrum-connection with and for controlling said yoke to swing the distributor pipe and also to move the same with said tube into projected or retracted position.
2. The combination with a supply - pipe, and a stationary casing connected therewith, of a steam pipe extending from said casing, a tube journaled therein, a distributor pipe 15 extending radially from said tube, a rod connected with said tube, and an oscillatory lever connected with said rod and having a fulcrum connection with said casing for reciprocating and rotating said rod.
3. The combination with a supply pipe, and a stationary casing connected therewith, of a steam pipe extending from said casing, a tube journaled therein, a distributor pipe 20 extending radially from said tube, a rod connected with said tube, an oscillatory lever connected with said rod, and a fulcrum link connecting said lever and casing.
4. The combination with a supply pipe, and a stationary casing connected therewith, of a steam pipe extending from said casing, a tube journaled therein, a distributor pipe 25 extending radially from said tube, a rod connected with said tube, an oscillatory lever connected with said rod, and a fulcrum link connecting said lever and casing.
5. The combination with a supply pipe, and a stationary casing connected therewith, of a steam pipe extending from said casing, a tube journaled therein, a distributor pipe 30 extending radially from said tube, a rod connected with said tube, and an oscillatory lever connected with said rod, a link pivoted on the lever and having a pin adjustably
- mounted on said casing for varying the position of the lever.
6. The combination with a supply pipe, and a stationary casing connected therewith and having an extension provided with 40 spaced apertures, of a steam pipe extending from said casing, a tube journaled therein, a distributor pipe extending radially from said tube, a rod connected with said tube, a lever pivoted on said rod, a link pivoted on the lever and having a pin adapted to enter any one of said apertures to vary the position of the lever.
7. In a blower for boilers, the combination with a furnace wall, of a steam tube extending therethrough, a perforated distributor pipe extending radially from said tube, a jacket of asbestos or the like inclosing said distributor pipe and a correspondingly perforated tube inclosing said asbestos and pipe 55 for the purpose specified.
8. In a blower for boilers, the combination with a furnace wall, of a steam tube extending therethrough, a perforated distributor pipe extending from said tube, a jacket of asbestos or the like inclosing said distributor pipe, a perforated tube inclosing said asbestos and nipples connecting said pipe and tube.
9. In testimony whereof I affix my signature 60 in presence of two witnesses.
- HARRY A. HIGGINS.
